(57) CLAIM

I claim the ornamental design for a golf accessories pouch, as shown and described.

DESCRIPTION

FIG. 1 is a three-dimensional view of the golf accessories pouch.

FIG. 2 is a front view of the golf accessories pouch.

FIG. 3 is a rear view of the golf accessories pouch.

FIG. 4 is a left side view of the golf accessories pouch.

FIG. 5 is a right side view of the golf accessories pouch.

FIG. 6 is a top view of the golf accessories pouch.

FIG. 7 is a bottom view of the golf accessories pouch.

FIG. 8 is a three-dimensional view of the golf accessories pouch with the pockets and golf tee holding straps open, and with magnetically attachable belt/belt-line flap open; and, FIG. 9 is a three-dimensional view of the golf accessories pouch with the pockets and golf tee holding straps open, and the magnetically attachable belt/belt-line flap closed securing the device to a belt-line.

The broken lines illustrating stitching in the golf accessories pouch do form part of the claimed design. The broken lines illustrating environment in FIGS. 9-10 form no part of the claimed design.

1 Claim, 5 Drawing Sheets
